HIGH-FREQUENCY APPARATUS

Russell R. Law, Princeton, N. J., assignor to Radio Corporation of America, a corporation of Delaware

Application December 31, 1949, Serial No. 136,185

12 Claims. (Cl. 315—6)

1

This invention relates to ultra high frequency apparatus. More particularly it relates to improved ultra high frequency amplifiers and oscillators utilizing electron discharge devices and to an improved output coupling for preferred embodiments thereof.

As is known, it is common practice to employ electron discharge devices in circuits utilizing cavity resonators and wave-guides to produce oscillators and amplifiers, and that the physical structure of these arrangements either provides for, or at least does not prevent, cooling of the anode.

It is also desirable in some cases to cool the grid since it is usually fragile and therefore easily deformable by overheating. However in the past it has not been practical to provide such a cooling means because the grid supporting structure (for example the grid disc of a light-house triode) is usually contained within one or more metal housings where it cannot be reached by a cooling air blast.

Accordingly, it is an object of this invention to provide improvements for electron discharge device and cavity resonator assemblies of the character indicated so that means can be provided for cooling the grid of the discharge device.

Another object of the present invention is to provide an amplifier or oscillator assembly comprising in combination a discharge device and one or more cavity resonators coupled to elements thereof in which means are provided as an integral part of the assembly for affording improved cooling of the grid of the discharge device.

As will be disclosed in detail, in accordance with my invention one way of attaining this object is to mount an annular resonator around the grid-supporting structure. It has the shape of a hollow ring of very large diameter with respect to the shortest wavelength for its operating band. A large number of grid-cooling fins extend radially from the grid supporting structure into the interior of the resonator where they can be cooled by a blast of air passing through the resonator. However certain difficulties arise because such a resonator is quite prone to multimoding and cannot be satisfactorily coupled to a load by preferred conventional means, such as by an inductive output loop, which disturb its concentric symmetry without aggravating this weakness. This is particularly true if the load is to be reached over a small-diameter coaxial output system.

Accordingly, it is a further object of the present invention to devise an amplifier or oscillator assembly of the character set forth above which in-

2

cludes a large-diameter annular cavity resonator and associated therewith an output circuit and transformer coupling means which does not increase the tendency of said resonator to multimoding.

In general according to one feature of the present invention a cavity resonator which surrounds the grid supporting structure comprises one or more walls which electrically are affectively continuous but physically are open to permit passage of a fluid cooling medium such as air, whereby this medium can be circulated within the resonator. An annular row of cooling vanes which are mounted outside of the tube envelope and extend from the periphery of a thermally-conductive grid-supporting structure into the path of said cooling medium extend into the physical structure of the resonator. These vanes are so closely spaced that their edges effectively define 10 interior electrical surfaces of the resonator. The row of grid-cooling vanes may extend into the structure of the resonator between two physically open end walls of the resonator or it may be positioned opposite one such end wall and itself serve 15 as the other.

In the drawing:

Fig. 1 is an end view of a plural-cavity electron discharge device, embodying the invention;

Fig. 2 is a longitudinal sectional view taken on 20 the line 2—2 of Fig. 1; and

Fig. 3 is a longitudinal sectional view of an alternative embodiment of the invention.

An ultra high frequency amplifier is represented in Figs. 1 and 2 of the drawing. As best shown 35 in Fig. 2 it comprises an indirectly heated cathode 10 having a flat circular emissive coating 11. Supported adjacent to the coating 11 and closely spaced therefrom is a flat circular control grid 12 which is supported by its edges in a central opening in the right hand metal wall 13 of a cathode-grid cavity resonator 15. This wall and preferably all of the walls of the resonator 15 should be made of conductive material such as copper (whether or not they have their interior surfaces silver plated) to the end that a means is provided 40 for conducting heat away from the grid 12.

Since the grid 12 is an integral part of the resonator 15 and since in the operation of the amplifier it is necessary to establish an appropriate direct potential bias between the cathode and the control grid, it is essential to provide direct 45 current insulation between the cathode thimble 16 and the body of the resonator 15. However, it must be remembered in this connection that the inner walls of the cavity must not be electrically 50 55

discontinuous as to alternating currents in directions along which radio frequency currents must flow during the operation of the device. Accordingly, the direct current insulation herein provided between the thimble 16 and the body of the resonator 15 is employed in an arrangement (a radio frequency "by-pass") which affords very low capacitive reactance between them. As shown in Fig. 2 this is accomplished by mounting the thimble 16 coaxially within a tubular extension 17 which protrudes leftward from the left wall 18 of the resonator 15 and may be in the form of an extrusion drawn from the center of that wall or of a separate part attached thereto.

Fitted tightly into the very small space between the thimble 16 and the sleeve 17 is a cylindrical insulating shim or spacer 19 which preferably should be of a material, such as mica, having a high dielectric constant. In the arrangement shown in Fig. 2 it is not necessary that the shim 19 fit so accurately as to form a vacuum seal between the outside of the thimble 16 and the inside of the sleeve 17. Instead a small glass bulb 20 is placed over the left end of the entire cathode-mounting assembly and its edges are sealed to the outside of the sleeve 17 as shown. Sealed through the left end of this bulb are a pair of leads 22, 23 for the cathode heater 24 (these leads and the heater are insulated from the cathode thimble by a means, not shown, such as by a coating of aluminum oxide) and a lead 25 which extends from the cathode thimble 16.

An anode 27 consisting of a thick circular disc of electrically and thermally conductive material such as copper is supported on the right hand side of the outside surface of the wall 13 with appropriate spacing therefrom so that the coating 11, the grid 12 and the left surface of the anode 27 comprise an ultra-high frequency triode. The anode 27 is supported in this position by a ring of glass 28 which forms a vacuum seal between the wall 13 and the anode 27. From the foregoing it is apparent that all of the space within the resonator 15, the bulb 20 and the cathode thimble 16, as well as the space between the resonator and the anode is sealed from the outer atmosphere so that it may be pumped down to a hard vacuum. A means for coupling an input signal to the resonator 15 is provided at 30, it having the form of an inductive loop which is mounted within the resonator and is connected to a coaxial fixture on the outside thereof.

Resonator 15 may be considered as comprising one lumped capacitance between the coating 11 and the grid 12 and a number of parallel shunt inductances. The inductances are afforded by conductive paths which extend axially along the outside of the thimble 16 between the coating 11 and the wall 18; radially along the inside surface of the wall 18 between the cathode thimble and the inside of the cylindrical wall 21 of the resonator; axially along the inside of the wall 21 between the walls 13 and 18; and radially along the inside of wall 13 between the wall 21 and the grid 12. In the operation of this amplifier an electric field which changes in accordance with the input signal will be established across the capacitive gap between the coating 11 and the grid 12 to control the discharge current of the triode.

A grid-anode cavity resonator 32 is shown which electrically is very similar to resonator 15 but physically is quite different from it. The wall of resonator 32 which electrically corresponds to the wall 13 of the resonator 15 is composed of a

plurality of fins 33 which extend radially from the cylindrical periphery of anode 27 to the inner surface of a metallic cylindrical rim 35 to each of which they are connected for example with silver solder, to form a rigid structure and to provide low impedance electrical and thermal conduction from the anode to the rim. The fins 33 are so closely spaced that even for the shortest wavelength at which this amplifier is intended to operate their leftward-facing edges will define an electrically unbroken surface corresponding to the inner surface of the wall 13. The cylindrical outer wall of resonator 32 consists of a large-diameter cylinder 36 in the right end of which the rim 35 is mounted. A thin dielectric spacer 37 is fitted between the cylinder 36 and the rim 35 to provide a direct current open circuit between the anode and the grid and a radio frequency by-pass across it.

In the operation of this amplifier sources of direct potentials for the grid and the anode may be individually connected to the structural assemblies which respectively immediately surround these elements.

A second group of fins 38 are arranged in an annular row around the outside of the resonator 15. From the foregoing it is apparent that in the operation of this amplifier heat generated at the grid 12 will be conducted along the wall 13, thence to the cylindrical wall 21 and thence to the fins 38 from which it can be dissipated by a blast of cold air directed as indicated by the arrows 40. Because of the close spacing of the fins 38 their inwardly facing edges 41, 42 and 43 are effective to define some of the internal electrical boundaries of the resonator 32. Since in the preferred mode of operation for the resonator 32 (i. e., in the zero mode) radio frequency currents will tend to move in directions corresponding to those already described for resonator 15, it is apparent that they will encounter only low impedance paths, i. e., paths along the edges of the fins 33 and 38, despite the physically open nature of the structure. Therefore the resonator 32 not only will be operative but may even have a desired high value of Q .

Means for withdrawing energy from the output resonator 32 is shown at 45 in the form of an inductive loop mounted within the resonator and connected to an external coaxial fixture by a conductor which extends out of the resonator between two of the vanes 38.

The embodiment of Fig. 3 resembles that of Fig. 2 in many respects. However in it the resonators are of the annular type which of course may be of very large diameter in terms of wavelength and therefore particularly susceptible to multimoding; it includes a means for coupling the large-diameter resonator 32' to a small-diameter coaxial output line without disturbing the cylindrical symmetry of that resonator (and thereby increasing its tendency to multimoding); and it is modified to act as an oscillator rather than an amplifier.

As will be understood by those familiar with the art in the sort of arrangement of annular resonators which is shown in Fig. 3, certain space such as the space between the two brackets x, y , is "dead space," i. e., space which has no material effect on the operation of the resonators and does not materially add to the volume of their resonant spaces, this being true because of the negligible amount of capacitance between the set-back surfaces in the central re-

gions of the cathode and the anode. It will be noted that because of the modified form of the cathode thimble 16' the emissive coating 11' is annular rather than circular and the heater 24' is wound as a large-diameter spiral rather than as a small helix.

Besides the novel coupling means shown herein in an additional factor contributing to the stability of this oscillator is the fact that the above-described physically-open type of structure, which is also used for some of the walls of resonator 32', tends to confine the flow of current in certain predetermined directions.

Obviously the operating frequency of a resonator like resonator 15 of Fig. 2 will be increased without increasing its overall diameter if it is modified to have the annular form shown for resonator 15' in Fig. 3. This is due to the fact that the modification results in a considerable reduction in the distance measured around the inside of a cross-section of the resonator taken in a plane normal to the annular axis of the resonator from one side of the capacitive gap to the other, i. e., from the emissive coating to the grid. Accordingly, in Fig. 3 the diameter of the annular axis of the resonator 15' may be large or even very large with respect to the wavelength corresponding to the operating frequency of the oscillator. It is assumed that resonator 32' will be designed with a resonant frequency corresponding to that of resonator 15'.

Feedback from the cavity 32' to the cavity 15' takes place through a plurality of equally spaced R. F. "windows" 50 each of which consists of an opening in a common wall between the resonators 32' and 15' and a vacuum-tight seal of dielectric material across the opening. Since small openings will usually provide sufficient feedback and since these openings are evenly spaced, they will not materially disturb the symmetry of the large-diameter annular cavity 32'. However, if desired, the feedback means may be made with the even more symmetrical form of a very narrow slot extending all the way around the cylindrical wall 21'.

In the Fig. 3 embodiment each of the fins 38 of the Fig. 2 embodiment is replaced by two fins, 52, 53 which may be considered as formed from this fin 38 by cutting away an appropriate portion thereof so that the resonant space within the resonator 32' extends to the wall 21' with the result that part of it becomes a common wall in which the feedback means may be located and so that the resonant space also extends to a cylindrically symmetrical opening 55 through which output energy may radiate over a transformer arrangement 56 into an output line 57. This includes a large-diameter concentric line 59 whose inner and outer conductors 60 and 61 are of such sizes that the space between them coincides with the opening 55 and that the outer conductor 62 of line 57 fits within the inner conductor 61 with a considerable amount of clearance all the way around.

As is known, the surge impedance of a concentric line is not solely a function of its overall largeness of diameter but also of the ratio of the inside diameter of its outer conductor to the outside diameter of its inner conductor. Therefore it should be borne in mind that the surge impedances of the respective lines 59 and 57 will not necessarily have a disparity corresponding to that between the overall diameters of these lines. Generally speaking, however, the smaller of the two lines will usually have the lower impedance.

It is known to use transformers connected between two unequally-proportioned coaxial lines, each of which lies along an extension of the axis of the other, which transformers comprise tapered inner and outer conductors each acting alone to provide a smooth transition between the corresponding (inner or outer) conductors of the two lines and both acting together to provide a smooth transition between the inter-conductor spaces of the two lines. However, in certain installations the extension of the length of the circuit which this necessitates may be undesirable. To avoid this difficulty there is shown herein a transformer section 65 which extends radially between cylindrically symmetrical windows formed respectively in the inner conductor 61 of the line 59 and the outer conductor 62 of the line 57. Assuming a higher impedance for line 59 than line 57 the transformer section 65 should taper outward toward the point where it is coupled to the window 66 of the inner conductor 61. That is to say, the structure of the transformer section should then resemble two frusto-conical cones having the small ends facing one another and spaced slightly apart.

The opening 66 is mechanically closed, by a dielectric material which will permit R. F. freely to radiate through it, so that all of the inner conductor 61 remains an integral unit and so that the entire line 57 can be moved axially of the oscillator to move the window 66 along a coaxial stub formed between the conductors 60 and 61. This stub is completed by a shorting element 70 which is inserted into its open left hand end and can be moved leftward and rightward in it. In the operation of this oscillator the shorting element 70 is moved to match line 59 to the oscillator. This will set up a certain standing wave distribution within the coaxial stub 59. Thereafter the assembly comprising the line 57, the transformer section 65, and the conductor 61 is moved axially of the oscillator so that an impedance match is attained between the load as seen through the opening 66 looking inward into the transformer 65 and the source as seen therethrough looking outward into the stub. It will be noted that in the embodiment of Fig. 3 the cylindrical outer wall 21' of the resonator 15' includes an extension 21" which serves as the male portion of a trombone arrangement which is completed by the inner conductor 61 as shown in the drawing. In order to assure satisfactory contact where conductor 61 slides over extension 21" the conductor 61 may be axially slotted to form a plurality of spring fingers according to known techniques. Similar fingers may also be used in forming the shorting means 70.

If perchance the two lines 57 and 59 should have the same surge impedance despite the disparity between their overall diameters it would not be necessary to provide any radial taper for the transformer section 65.

It is conceivable that in some particular embodiments of the present invention, the small diameter line may actually have a higher impedance than the larger line due to the use of wide spacing between its conductors. In such a case, if desired, the taper of the transformer section 65 may be reversed so that in effect it is built up of two frusto-cones whose large ends are nearest together.

Moreover, it is possible within the scope of the present invention to utilize the transformer 65 for feeding and matching to a cylindrical waveguide.

The advantage of the present arrangement of its not increasing any tendency of a large-diameter annular resonator to multimoding will not be affected by the mode in which the physically-small output system is excited or by the fact that this is different from the fundamental mode of that resonator.

While certain specific embodiments have been illustrated and described, it will be understood that various changes and modifications may be made without departing from the spirit and scope of the invention.

What I claim as new is:

1. A high frequency apparatus comprising an evacuated envelope, a pair of electrodes each having a surface which is cooperatively spaced from a surface of the other and is located within the envelope, a respective means including a metallic surface external to said envelope for conducting heat from each electrode through the envelope to said metallic surface, a row of external cooling fins extending from each of said metallic surfaces, a hollow cylindrical member in electrical contact with the fins of each row, some of the inside surface of said member and inwardly facing edges of the fins of said rows defining interior surfaces of a cavity of a resonator.

2. A high frequency apparatus comprising a discharge device including an evacuated envelope, and therewithin a cathode, a control grid, and an anode surface; means including a metallic surface external to said envelope for conducting heat from said grid through said envelope to said metallic surface; a row of external cooling fins extending from said metallic surface; a hollow conductive member surrounding at least a portion of said row of fins and forming therewith a cavity resonator.

3. A high frequency apparatus comprising an electron discharge device having a first electrode and radially directed fins electrically connected to said electrode, said device having a second electrode spaced from said first electrode and radially directed fins electrically connected to said second electrode, and conductive means surrounding said fins and forming therewith a cavity resonator, said fins being closely spaced to form walls electrically closed to radio frequency currents for the resonant frequency of the resonator but physically open to a coolant passing into and out of said resonator.

4. A discharge device comprising an evacuated envelope, within the envelope an electron emissive surface, a control grid and an electron receiving surface positioned in the order named along a discharge path with the grid extending transversely to and across said path, a thermally conductive structure surrounding and supporting the grid, a plurality of heat dissipative fins arranged in an annular row and extending radially from said structure into a cooling medium outside of said envelope, a cavity resonator physically surrounding at least a portion of the annular row of fins, the fins being so closely spaced and disposed in such directions that edges thereof which face toward the inside of the resonator effectively define continuously-radio-frequency-conductive interior boundary surfaces thereof.

5. A discharge device comprising an evacuated envelope, within the envelope an electron emissive surface, a control grid and an electron receiving surface positioned in the order named along an axis with the grid extending transversely to and across said axis, a thermally conductive structure surrounding and supporting

the grid, a plurality of heat dissipative fins arranged in an annular row and radially extending from said structure into a cooling medium outside of said envelope, a first cavity resonator including said thermally conductive structure as at least a part of one of its walls and having a capacitive gap between said electron emissive surface and said grid, a second cavity resonator surrounding at least a portion of said first cavity resonator and of said annular row of fins, the fins being so closely spaced and disposed in such directions that outer edges thereof which face toward the inside of the second resonator effectively define continuously-radio-frequency-conductive interior boundary surfaces thereof, said second resonator having a capacitive gap between said grid and said electron receiving surface.

6. An electron discharge device as in claim 5 in which an outer wall of said second resonator comprises a conductive structure having a plurality of openings each of which is of small size with respect to one wavelength of the lowest frequency of the operating band for said resonator whereby said wall will be physically permeable to a fluid cooling medium whereas electrically its inside surface will be effectively an unbroken conductor as to radio frequency currents.

7. A discharge device as in claim 5 which further comprises a cylindrical anode block including said electron receiving surface at one of its ends, and in which said second resonator includes an outer tubular conductive wall, and an end wall formed of an annular row of vanes which extend radially between the cylindrical perimeter of the anode block and the inside of said tubular wall.

8. An ultra high frequency system comprising a large diameter annular cavity resonator of cylindrical symmetry, coaxial therewith a small diameter coaxial output line for carrying R. F. energy between the cavity resonator and another portion of the system, a circular window formed in the resonator concentric with its axis providing part of a cylindrically symmetrical path for the transfer of radio frequency energy between the interior of the resonator and said small diameter line, a large diameter coaxial transmission line so proportioned that the spacing between its inner and outer conductors coincides with said circular opening and means for attaching one end of said large diameter line to said opening, the small line being coaxial with the large line and inserted within the inner conductor thereof, an opening of cylindrical symmetry in the inside conductor of the large line and in alignment therewith a similar opening in the outer conductor of the small line, a transformer electrically interconnecting the large and small diameter lines for matching the impedances thereof, said transformer comprising a transition section extending radially between the respective openings of cylindrical symmetry of said inner conductor of the large line and said outer conductor of the small line.

9. An ultra high frequency system as in claim 8 in which the characteristic impedances of said two lines are unequal and said transition section is tapered radially for matching impedances which each presents to the other.

10. An ultra high frequency system as in claim 8 further comprising means for terminating the other end of said large diameter line in a reflective impedance substantially unequal to

the characteristic impedance of said line to cause it to act as a resonant stub and to set up standing waves therein during the operation of the system, and means for moving along said stub the opening of cylindrical symmetry which is formed in its inner conductor, said last-mentioned means comprising means for moving the transition section together with said opening to maintain coupling therebetween for all positions thereof.

11. A high frequency system comprising a large diameter coaxial transmission line, the inner conductor of said line having an opening of cylindrical symmetry, a small diameter hollow conductor also having an opening of cylindrical symmetry and being inserted within the inner conductor of the large diameter line to a point where said openings are in predetermined alignment, and a transition section formed of a pair of oppositely disposed disc-like members each having inner and outer peripheries respectively terminating at corresponding sides of said respective openings for electrically interconnecting said respective openings.

12. A high frequency apparatus including a tuned circuit element of annular symmetry as the figure of revolution of a closed pattern about a center outside of said pattern, the tuned element enclosing space adapted to be resonant in a predetermined frequency range, said circuit element having outer and inner curved walls

whose respective interior surfaces face each other across said space the former facing the latter in directions which are radial toward said center and the latter facing the former in opposite directions, one of said curved walls having an opening of cylindrical symmetry, a hollow cylindrical conductor having a diameter which is different than that of either of said curved walls and is more nearly equal to that of the 10 curved wall having said opening than to the other, said hollow conductor being coaxially disposed with respect to the last-mentioned curved wall and axially positioned with respect thereto with their respective openings in predetermined 15 registry, and a transition section formed of a pair of oppositely disposed disc-like members each having inner and outer peripheries respectively interconnecting corresponding sides of said registered openings.
